UNITED STATES PATENT OFFICE.

ALMON W. COBLEY, OF PITTSBURGH, AND BENJAMIN H. SMITH, OF TURTLE CREEK,
PENNSYLVANIA, ASSIGNEES TO WESTINGHOUSE ELECTRIC AND MANUFACTURING
COMPANY, A CORPORATION OF PENNSYLVANIA.

ELECTRICAL PROTECTIVE DEVICE.

1,286,239.

Specification of Letters Patent.

Patented Dec. 3, 1918.

Application filed June 30, 1916. Serial No. 106,882.

To all whom it may concern:

Be it known that we, ALMON W. COBLEY, a citizen of the United States, and a resident of Pittsburgh, in the county of Allegheny and State of Pennsylvania, and BENJAMIN H. SMITH, a citizen of the United States, and a resident of Turtle Creek, in the county of Allegheny and State of Pennsylvania, have invented a new and useful Improvement in Electrical Protective Devices, of which the following specification is a continuation in part of copending application Serial No. 771,888, filed June 5, 1913.

15 Our invention relates to electrical protective devices and particularly to relays.

One object of our invention is to provide a time-limit relay having electrical means for obtaining its time-limit functions.

20 Another object of our invention is to provide a relay of the above indicated character that shall have an inverse time-limit for all values of current up to a predetermined value and a definite time-limit for all values 25 of current above the predetermined value.

A further object of our invention is to provide a relay of the above indicated character that shall have means whereby a definite time-limit may be obtained for all values 30 of current at which the device is adapted to operate.

Our present application is a continuation, in part, of our copending application, Serial No. 771,888, filed June 5, 1913.

35 In the carrying out of our invention, we provide a magnetizable core member, an armature, main and auxiliary windings and a saturable transformer so connected between the two windings that, according to the value 40 of the current at which it becomes saturated, the torque of the armature may be so regulated that it may be constant for all values of current traversing the main winding, or it may vary substantially as the current 45 traversing the main winding up to a predetermined value of current and be substantially constant above the predetermined value of current.

In the accompanying drawings Figure 1 50 is a diagrammatic view of a relay embodying our invention, and Figs. 2 and 3 are diagrammatic views of modified forms of relays embodying our invention.

A relay 1 is operatively connected to an electric circuit 2 and comprises, in general, 55 a magnetizable core member 3, a rotatable armature 4, a main winding 5, a secondary winding 6, auxiliary windings 7 and a saturable transformer 8.

The armature 4 is mounted upon a shaft 60 9 upon which is also mounted a movable bridging contact member 10 that is adapted to engage two stationary contact members 11 which constitute the terminals of a tripping device (not shown). The inner end 65 of a relatively light spring 12 is operatively connected to the shaft 9 and its outer end is connected to a stationary member 13. The armature 4 is adapted to turn between the poles of permanent magnets 14 for the purpose 70 of damping or retarding its movements. The main winding 5 of the relay 1 is operatively connected to the secondary winding 15 of a current transformer 16, and the secondary winding 6 of the relay 1 is 75 operatively connected to a primary winding 17 of the saturable transformer 8. A secondary winding 18 of the transformer 8 is operatively connected to the auxiliary windings 7 of the relay.

When a predetermined overload occurs upon the circuit 2, current proportional to the current that traverses the circuit 2 will traverse the main winding 5 of the relay and this current will induce a voltage in the 80 secondary winding 6 which, by reason of the closed-circuit relation with the winding 17 of the transformer 8, will cause a current to traverse the winding 17. The current traversing the winding 17 will induce a voltage 85 in the winding 18 and this will cause current to traverse the auxiliary windings 7 of the relay. Thus, a shifting flux is set up in the air gap of the relay 1 that causes the armature 4 to turn against the action of the 90 spring 12 to effect engagement between the bridging contact member 10 and the stationary contact members 11. The flux that causes the armature to turn may be assumed to be composed of two parts, one substantially 95 proportional to the current traversing the circuit 2 and the other substantially constant by reason of the partial magnetic saturation of the transformer 8. Thus, the armature 4 will develop a torque substantially 100 proportional to the current traversing the 105

winding 5, under predetermined conditions. However, if the transformer 8 is worked above the knee of its saturation curve, the phase-angular relation between the two 5 fluxes is materially reduced and, thus, the torque of the armature 4 will decrease. Consequently, at a predetermined value of current, depending upon the magnetic saturation of the transformer 8, the torque de- 10 veloped by the armature 4 will become substantially constant for all values of current traversing the winding 5. That is to say, the time required for the contact member 10 to engage the contact members 11, after 15 a predetermined overload traverses the circuit 2, will vary substantially inversely as the current traversing the circuit 2, up to a predetermined overload, and will be substantially constant for all values of overload 20 above the predetermined value.

In Fig. 2 of the drawings, the magnetizable core member 3 is provided with a magnetizable armature 19 that is supported by springs 20. The armature 19 is provided 25 with contact members 21 that are adapted to engage stationary contact members 22 for the purpose of closing the circuit between the winding 6 of the relay 1 and the winding 17 of the transformer 8, under pre- 30 determined conditions.

In Fig. 2 of the drawings, when a predetermined overload occurs upon the circuit 2, sufficient current will traverse the main winding 5 to move the armature 19 downwardly. Thus, the armature 4 will not creep or operate until the contact members 21 and 22 are engaged. If the current required to operate the armature is of such value as to induce sufficient voltage in the winding 6 35 to cause the transformer 8 to be saturated above the knee of its saturation curve, it will be understood that the torque developed by the armature 4 will be substantially constant. In other words, the armature 19 is 40 provided for the purpose of so controlling the windings of the relay that the contact member 10 will engage the contact members 11 in a definite time, irrespective of the over- 45 load traversing the circuit 2.

In Fig. 3 of the drawings, the armature 19 is provided with a contact member 23 that is adapted to be normally held in engagement with a stationary contact member 24 by the spring 20. The contact members 55 23 and 24 constitute the separable terminals of a short-circuit connection 25 across the terminals of the winding 17 of the transformer 8.

When a predetermined overload occurs 60 upon the circuit 2 and the modified form of our invention shown in Fig. 3 is employed, the armature 19 will be moved downwardly to open the short-circuit connection 25 around the winding 17 to thus permit the 65 winding 18 to energize the auxiliary wind-

ings 7 which, in connection with the main winding 5, cause the armature 4 to turn against the action of a light resetting spring (not shown) with a substantially constant torque, substantially as set forth with respect to the device shown in Fig. 2 of the drawings.

It will be understood that, if the armature 19 is omitted from the modified forms of our invention, shown in Figs. 2 and 3, 75 the devices will operate in substantially the same manner as the device shown in Fig. 1 of the drawings. It will be further understood that the time required for the contact members 10 and 11 to engage may be 80 changed by varying the size of the core and the number of turns of the windings of the transformer 8 in order that it may become saturated, under predetermined conditions. Thus, the time of operation of the 85 relay may be either definite under all conditions or inverse up to a predetermined value of current and definite for all values of current above the predetermined value.

We do not limit our invention to the particular arrangements illustrated, as it may be variously modified without departing from the spirit and scope of the invention as set forth in the appended claims.

We claim as our invention:

1. A relay comprising a magnetizable core member having a main and an auxiliary winding thereon, an armature and a transformer connected between the main and the auxiliary winding for causing a constant 100 torque to be exerted on the armature for all values of current traversing the main winding above a predetermined value.

2. A relay comprising a magnetizable core member having a main and an auxiliary 105 winding thereon, an armature, and a reactance device connected between the main and auxiliary windings for causing the armature to develop a constant torque for all values of current traversing the main winding above 110 a predetermined value.

3. A motor comprising a magnetizable core member having a main and an auxiliary winding thereon, an armature and means connected in circuit with the said auxiliary 115 winding to coöperate with the main winding to cause the armature to develop a substantially constant torque when current in excess of a predetermined value traverses the main winding.

4. A relay comprising a magnetizable core member having a main and an auxiliary winding thereon, an armature and electrical means connected in circuit with the said auxiliary winding to coöperate with the main 125 winding to cause the armature to develop a substantially constant torque when the current traversing the main winding exceeds a predetermined value.

5. A relay comprising a magnetizable core 130

member having a main and an auxiliary winding thereon, an armature and means interposed in the circuit of the said auxiliary winding that coöperates with the said main winding to cause the armature to develop a substantially constant torque when the current traversing the main winding exceeds a predetermined value.

6. A relay comprising a magnetizable core member having a main and an auxiliary winding thereon, an armature and a reactor interposed in the circuit of the said auxiliary winding that coöperates with the main winding to cause the armature to develop a substantially constant torque when the current traversing the main winding exceeds a predetermined value.

7. A relay comprising a magnetizable core member having a main winding, an auxiliary winding and a secondary winding thereon, and a normally magnetically saturated transformer having two windings thereon, one of the transformer windings being connected in circuit with the auxiliary winding and the other transformer winding being connected in circuit with the said secondary winding.

8. A relay comprising an armature, a main winding, an auxiliary winding, and a transformer associated with the said windings and adapted to become magnetically saturated when a predetermined current traverses the main winding to cause the armature to develop a substantially constant torque for all values of current in the main winding above the predetermined value.

9. A relay comprising a magnetizable core member having a main and an auxiliary winding thereon, an armature, a magnetically saturable transformer interposed between the said main winding and the said auxiliary winding and means dependent upon the current traversing the main winding for controlling the circuit of the auxiliary winding.

10. A relay comprising a magnetizable core member having a main and an auxiliary winding thereon, an armature, means connected in circuit with the said auxiliary winding to coöperate with the main winding to cause the armature to develop a substantially constant torque when the current in the main winding exceeds a predetermined value, and means dependent upon the current traversing the main winding for controlling the circuit of the auxiliary winding.

11. A relay comprising an armature, a magnetizable core member, a main winding and an auxiliary winding disposed on the core member, and a transformer interposed between the main and auxiliary windings

and adapted to become saturated under predetermined conditions to cause the armature to develop a substantially constant torque under these predetermined conditions.

65

12. A relay comprising an armature, a main winding, an auxiliary winding, and means connected between the said windings whereby a substantially constant torque is exerted upon the armature when the current traversing the main winding exceeds a predetermined value.

13. A relay comprising an armature, a main winding, an auxiliary winding, and means operatively connected between the auxiliary and main windings whereby a substantially constant torque is exerted upon the armature when the current traversing the main winding exceeds a predetermined value.

30

14. A relay for an electric circuit comprising an armature, windings therefor and means connected between the windings for causing the armature to develop a torque that varies substantially directly as the current traversing the circuit up to a predetermined value of current and a substantially definite torque above the predetermined value of current.

15. A relay comprising an armature, a main winding, an auxiliary winding and means operatively connected between the said windings whereby a torque is exerted on the armature that varies directly as the current traversing the main winding up to a predetermined value and a substantially constant torque is exerted upon the armature above the predetermined value of current.

16. A relay for an electric circuit comprising a magnetizable core member having two coöperating windings thereon, an armature, and means connected between the two windings whereby a torque is exerted on the armature in accordance with the current traversing the circuit up to a predetermined value and a constant torque is exerted thereon for all values of current traversing the circuit above the predetermined value of current.

17. A relay comprising a magnetizable core member having a main and an auxiliary winding thereon, an armature and electrical means connected in circuit with the said auxiliary winding for causing a constant torque to be exerted on the armature for all values of current traversing the main winding above a predetermined value.

In testimony whereof, we have hereunto subscribed our names this 29th day of June, 1916.

ALMON W.-COPELEY.
BENJAMIN H. SMITH.
